THOMAS A. BOYD AND HAROLD A. BOYD, OF SHETTLESTON, NEAR GLASGOW,
SCOTLAND.

COP AND PIRN WINDING MACHINE.

Application filed February 27, 1922. Serial No. 539,562.

To all whom it may concern:

- Be it known that we, THOMAS ALEXANDER BOYD and HAROLD ARTHUR BOYD, subjects of the King of the United Kingdom of Great Britain and Ireland, and residing at Shettleston, near Glasgow, Scotland, have invented a certain new and useful Improvement in Cop and Pirn Winding Machines, of which the following is a specification.
- 10 Our invention refers to cop or pirn winding machines hereinafter termed simply cop winding machines in which a "feeler" is used to regulate the relation of the thread guide to each cop, whereby to determine the diameter to which the cop is wound.
- 15 (By the word "feeler" is meant a member which is intermittently touched by the yarn being wound on to the cop for the purpose of regulating the diameter of the cop).
- 20 More particularly our invention refers to improvements in the construction of such feelers and means for operating the same and in winding machines of the kind described.

- 25 Our invention comprises a feeler which is rotated before the yarn being wound upon the cop comes in contact with the feeler; it also comprises means for forming the bottom on such a cop by the action of a pusher shaft operating one or more feelers, and means for stopping individual winding spindles serving feelers on winding machines of the kind described.

- 30 In the accompanying drawings Fig. 1 is an end sectional view of a machine embodying the invention. Figs. 2 and 3 are full size detail views of the frictional driver for the feeler. Fig. 4 is a detail view of the pusher shaft for forming the cop bottom. Fig. 5 shows a feeler with a detachable cone.

- 35 In a practical example of our invention embodied in a machine for winding fine cotton or silk yarn on to a paper tube to form a weft cop we employ a pair of spindle rails 1, 1 disposed parallel to one another and at the same level, located at a convenient distance apart, and extending from end to end of the machine. At right angles to the spindle rails 1, 1 at suitable distances apart we 40 mount winding spindles 2 such as in bearings 3, 3. We shall describe in detail the arrangement and operation of one spindle. Mounted on the spindle between the spindle rails 1, 1 is a wharve 3¹ which is driven by a

tape 4 coming from a tin roller 5 placed at 55 a convenient distance below and parallel with the spindle rails 1, 1. The tin roller 5 is carried on bearings and extends from end to end of the machine and constitutes the main driver of the same. The spindle 2 extends to the front of the machine and placed on its outer end 2¹ is a paper tube 6 on which the yarn is to be wound. The spindle 2 extends behind the spindle rails 1, 1 and on its inner end 2² is a buckle 7 with a cross pin 8 60 at right angles to the spindle 2. Below the inner end of the spindle 2 we mount parallel with the spindle rails 1, 1, an oscillating traverse shaft 9. On the traverse shaft 9 below the spindle buckle 7 we fix a wiper 10 which 65 engages with the pin 8 in the buckle 7 and imparts to the spindle 2 a longitudinal traverse. Below the outer end 2¹ of the spindle 2 and parallel with it we mount a slide rod 11 whose inner end 11¹ is supported on a 70 bracket 12 fixed to the front spindle rail 1, and whose outer end 11² extends to a suitable distance in a stay rail 13 extending from end to end of the frame parallel with the said spindle rail 1. On the slide rod 11 we mount 75 a feeler slide 14 having a feather entering a key-way 11³ on the upper side of the slide rod 11. At the front end of the feeler slide 14 we form a projection 14¹ extending upwards and having a hole 14² coaxial with the 80 spindle 2. We fix in the hole 14² a ball bearing 15 carrying a feeler 16 having a central hole formed conical at its inner end 16¹ to receive the paper tube 6 on the spindle 2. The conical end of the hole is of the shape of 85 the yarn wound upon the cop, after the cop bottom is formed.

90 On the feeler 16 we form a boss 16² between the ball bearing and the apex of the conical hole in the feeler 16. Through the 95 boss 16² we make a flattened hole 16³ into which we insert a frictional driver 17, Figs. 2 and 3. The frictional driver 17 is made of wood with two layers of leather fixed on one side. We bore through the frictional driver 17 a hole 17¹ of diameter suitably larger than the diameter of the paper tube 6. Through the leather we form a hole 17² of less diameter than the paper tube. These 100 holes in the driver are coaxial with the cop and spindle.

105 We make radial slits around the hole 17² in the leather to allow the paper tube

6 to be traversed longitudinally through the leather and with sufficient catch of the paper tube 6 to be driven by it when winding is proceeding.

5 On the feeler slide 14 we fix a thread guide 18 clear of the wide end of the cone. The yarn to be wound is drawn from a hank or other source and is guided on to the paper tube 6 which with the outer end of 10 the spindle 2 has entered the feeler 16.

After the bottom of the cop has been formed as hereafter described, and while the winding is proceeding, the traverse of the spindle brings the yarn on the cone or bottom 15 of the cop against the conical hole of the feeler 16 and gradually forces the feeler 16 and the slide 14 away from the spindle 1 and cop or tube 6, thus locating the thread guide to form the cop. As the paper tube 6 is traversed into the feeler 16, the friction of the leather on the frictional driver 17 on the paper tube 6 rotates the feeler 16 so that it is running approximately at the speed of the cop or tube 6 when the yarn on 20 the cop is pressed against the conical hole in the feeler 16.

Formed on the outer end of the feeler slide 14 below the slide rod is a double jaw 14³ projecting downwards and open up to the 30 slide rod 14. In the double jaw 14³ we mount a brake lever 18¹ carrying a weight 18¹ at its outer end and at its inner end 18² a wood block 19 pressing on the lower side of the slide rod 11. By this means 35 sufficient resistance is given to the cop as it presses on the feeler 14 to ensure a firmly built cop. The pressure of the yarn being against a feeler which before the moment of touch is running at its own speed, 40 there is no such rubbing of the yarn as there would be if the feeler had to be revolved by the pressure of the yarn or if the feeler were stationary.

The spindle may be stopped automatically 45 by the movement of the feeler when the cop is filled, or by hand at will.

With this object in view, we mount on the framing a horizontal bar 20 at about the same level as the tin roller 5 and at a 50 suitable distance behind the tin roller 5. On the bar 20 we fix a bracket 21 on which we pivot a tension lever 22 extending over the top of the tin roller 5 and carrying a tension pulley 23 resting on the upper side 55 of the tape 4. By means of this tension lever 22 and its pulley 23 the tape 4 is tensioned to give sufficient drive for the spindle 2. To stop the spindle 2, we lift the tension lever 22 and pulley 23 off the tape 4. 60 For lifting the tension lever 22 we mount on the under side of the front spindle rail 1 in a bracket 24 a horizontal stop lever 25 located in the same vertical plane as the spindle 2. The stop lever 25 extends outwards and at its outer end 25¹ is a jointed

catch lever 26 extending upwards and engaging a catch plate 27 fixed upon the slide rod 11. The inner end 25² of the stop lever 25 extends to a point over the pulley end 22¹ of the tension lever 22 and attached to it is a lifting rod 28 whereby the tension lever 22 is lifted when the catch lever 26 is released and the stop lever 25 drops at its weighted outer end 25¹. Thus, the tape 4 is slackened and the spindle 2 stops. 70

On the inner end 14⁴ of the feeler slide 14 we fix a stop wire 29 extending inwards and bent behind the catch lever 26. This stop wire 29 engages with and draws the catch lever 26 off the catch 27 when the cop 80 is filled. To form a conical bottom of yarn on the paper tube 6 we mount on the framing parallel with the spindle rails 1 and below the feeler slide 14 a rotary pusher shaft 30. On the said pusher shaft 30 we

mount frictionally a pusher wiper 31 which engages with a projection 14⁵ on the feeler slide 14. A stop 31¹ which extends horizontally below the slide rod 11 limits the range of movement of the wiper with the shaft 30. The pusher shaft 30 is driven at reduced speed through gearing from the tin roller 5 and is caused to rotate so that the wiper 31 will press the feeler 14 outwards at a slower speed than does the yarn when the cop is being built. Thus, when starting to wind on a paper tube, the feeler slide and thread guide are gradually pushed outwards until the yarn forms in cone shape on the tube, and the feeler slide being pressed at a slower speed than the yarn builds at, the yarn gains upon and ultimately touches the feeler and pushes it outwards until the cop is fully formed. It will thus be understood that the yarn coming from the hank 90

is wound on the paper tube which is traversed to and fro past the thread guide, first forming the cop bottom and then pressing against the feeler and moving it and the thread guide outwards until the cop is 100 fully formed. The feeler being rotated before the yarn on the cop comes in contact with it, the pressure of the yarn on the feeler causes no damage to the yarn. On

completion of the cop the feeler operates the stop motion and slackens the tape, thereby stopping the spindle. To permit quick alterations of the feeler to suit cops of varying diameter and shape, we make the feeler (Fig. 5) with a detachable conical end 32 which may, for example, be threaded into a support 33 carried by the ball bearing 15. 110

We claim:

1. In a pirn or cop winding machine, in combination, a feeler, and means for rotating the feeler before the yarn being wound upon the pirn or cop comes in contact with the said feeler for the purposes described. 125

2. In a pirn or cop winding machine, in combination, a feeler, a rotary spindle, and 130

a frictional transmission device for effecting rotation of the feeler before it is contacted by the yarn being wound.

3. In a pirn or cop winding machine, in combination, a rotary spindle, a feeler and a detachable frictional driver for effective rotation of the feeler before it is contacted by the yarn being wound.

4. In a pirn or cop winding machine, in combination, a winding spindle, a feeler coaxial with said spindle and movable endwise of said spindle by the pressure of the yarn, and means including a pusher shaft acting on the feeler in forming the bottom of a cop, substantially as and for the purposes described.

5. In a pirn or cop winding machine, in combination, a spindle adapted to be revolved and to be traversed longitudinally in the winding of a pirn or cop, a feeler coaxial with said spindle and penetrated by the spindle during the formation of the pirn or cop, and means controlled by the movement of said feeler for stopping the revolution of

said spindle substantially as and for the purposes described.

6. In a pirn or cop winding machine in combination, a ball bearing, a holder supported in said bearing and a detachable feeler in said holder, said feeler being held entirely outside said ball bearing, substantially as and for the purposes described.

7. In a pirn or cop winding machine, in combination, a rotatable feeler, a slidable carrier for said feeler, a spindle adapted to be traversed to and fro, means controlled by said feeler for stopping said spindle, and a pusher shaft operating the feeler for forming the cop bottom.

In testimony whereof we have signed our names to this specification in the presence of two subscribing witnesses.
